(57) **CLAIM**

The ornamental design for a portable hydrogen water mist sprayer, as shown and described.

DESCRIPTION

FIG. 1 is a perspective view of a portable hydrogen water mist sprayer showing my new design;

FIG. 2 is a front plan view thereof;

FIG. 3 is a rear plan view thereof;

FIG. 4 is a left-side plan view thereof;

FIG. 5 is a right-side plan view thereof;

FIG. 6 is a top plan view thereof; and,

FIG. 7 is a bottom plan view thereof.

The broken lines depict environmental subject matter only and form no part of the claim. In the drawings, the dot-dash lines represent boundaries of the claim and form no part of the claimed design.
